CLAIM

The ornamental design for a beard trimmer, as shown and described.

DESCRIPTION

FIG. 1 is a front, right and top perspective view of a beard trimmer, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the beard trimmer shown in an environment of use with a base. The broken lines depict portions of the beard trimmer that form no part of the claimed design. The broken line showing of the base in FIG. 9 depicts environment and forms no part of the claimed design.
